UNITED STATES PATENT OFFICE

JOSEPH BERGER, OF UTICA, NEW YORK, ASSIGNOR TO UNION SPECIAL MACHINE COMPANY, OF CHICAGO, ILLINOIS, A CORPORATION OF ILLINOIS

LOOPER MECHANISM FOR SEWING MACHINES

Application filed May 4, 1928. Serial No. 275,068.

The invention relates to new and useful improvements in a looper mechanism for sewing machines and more particularly to a looper mechanism for a sewing machine having a cylindrical work supporting arm containing a feeding mechanism for feeding the material lengthwise of the arm during stitching.

An object of the invention is to provide a machine of the above type with a looper operating mechanism wherein the looper has two motions only, a forward movement into the needle thread looper, and a retracting movement out of the needle thread loop, both of which movements are in a plane containing the line of feed.

A further object of the invention is to provide a machine of the above type with a loop spreader which is mounted for operation in a line at right angles to the path of movement of the loopers.

A further object of the invention is to provide a looper operating mechanism of the above type which may be mounted in a work supporting arm which, in turn, is suspended from the main frame of the machine and actuated by an eccentric on a main shaft in the main frame.

A still further object of the invention is to provide a machine of the above type wherein the loop spreader is also operated by a train of mechanism in turn actuated by an eccentric on the main shaft.

A further object of the invention is to provide a machine of the above type with a looper operating mechanism wherein the looper is given a relatively short movement and a quick movement into the needle thread loop where it is given an appreciable dwell.

These and other objects will in part be obvious and will in part be hereinafter more fully disclosed.

In the drawings which show by way of illustration one embodiment of the invention:

Figure 1 is a plan view of one type of sewing machine embodying the invention.

Fig. 2 is a front view partly in section of the same.

Fig. 3 is a side view of the operating mechanism within the work supporting arm, the work supporting arm being shown in broken lines.

Fig. 4 is a horizontal sectional view through a portion of the work supporting arm showing the parts within in plan view.

Fig. 5 is a plan view of the parts beneath the line 5—5 of Fig. 3.

Fig. 6 is a view partly in section and partly in end elevation of the work supporting arm showing particularly the loop spreader in side view.

Fig. 7 is a view similar to Fig. 6 but showing a different position of the loop spreader.

Fig. 8 is a perspective view of the carrier for the loop spreader and showing a portion of the shank of the loop spreader.

Fig. 9 is a diagrammatic view of the loopers and spreader showing the looper thread loops spread for the needles to enter.

Fig. 10 is a side view of the parts shown in Fig. 9.

The invention is directed to a looper mechanism for sewing machines, and more particularly to a sewing machine which has a cylindrical work supporting arm containing a feeding mechanism for feeding the material longitudinally of the arm. The looper mechanism includes a thread carrying looper mounted on a looper carrier which, in turn, is supported at the free end of the work supporting arm so that the looper may freely oscillate in a vertical plane containing the line of feed. The looper carrier is oscillated by a train of mechanism from a main shaft carried by the main portion of the frame from which the work supporting arm is suspended. The looper is a two motion looper, and, therefore, is oscillated about a fixed axis in a plane at right angles thereto.

A link connected with the looper carrier is, in turn, connected with a rock shaft adjacent the rear end of the work supporting arm and this rock shaft is oscillated by a second rock shaft adjacent thereto, and, in turn, connected to an eccentric on the main shaft. The connection between the two rock shafts and the connection between

80

85

95

100

the link and first named rock shaft are so formed as to move the looper quickly into the needle thread loop and give an appreciable dwell at the forward end of its stroke.

5 If two lines of stitching are desired, then two needles are used and two loopers provided which cooperate independently with the needles. Cooperating with the loopers is a loop spreader. This loop spreader is

10 mounted on a support which slides along a stationary bar arranged in a line at right angles to the plane of oscillation of the loopers. This loop spreader cooperates with both loopers when two loopers are used, and

15 to this end, is provided with two shoulders or hooks on the under face of the spreader. The spreader overlies the loopers and is timed so that the shoulders engage the looper threads of the respective loopers with which

20 they cooperate and move the thread away from the body of the looper so as to insure that the needles will pass between the thread and the looper. This loop spreader is moved laterally of the loopers by a rock lever lo-

25 cated adjacent the free end of the work sup-

30 porting arm which is oscillated by a link connected to a rock shaft at the rear end of the arm, and the rock shaft at the rear end of the arm is, in turn, operated by an eccentric on the main shaft. All of these

35 actuating parts are so mounted in the work supporting arm that the arm may be detached from the main frame with the as-

sembled parts therein, except for the eccen-

tric members on the actuating shaft.

Referring more in detail to the drawings:—

The invention is shown as applied to a sewing machine which includes a main sup-

40 porting frame 1 carried at the upper outer end of an overhanging bracket 2 which is supported on a base 3. Extending length-

45 wise of this main frame 1 is a main actuating shaft 4. The main actuating shaft 4 is driven by a suitable belt wheel 5 and the

50 shaft also carries a hand wheel 6 at the outer end. Mounted on this frame and pro-

55 jecting forwardly therefrom is a housing 7 in which a needle bar 8 is mounted for re-

ciprocity. This needle bar carries the

60 needles of the stitching mechanism. As

65 shown in the drawings, there are two needles 9 and 10 mounted on said needle bar. This

70 needle bar is reciprocated by a suitable

75 mechanism from the main shaft 4.

At the opposite end of the main frame 1 from the housing 7 is a depending member or housing 11. At the lower end of this depending member and closing the same is

80 a detachable work supporting arm 12. This

85 work supporting arm 12 is what is usually referred to as a cylindrical work supporting arm which is especially adapted for stitching tubular articles. The work supporting

90 arm 12 is suspended by this depending mem-

ber 11 and the material may be passed underneath the same and folded around onto the upper face of the arm and thus led to the stitching mechanism. As shown in the drawings, the machine is provided with a presser foot 13 carried by a presser bar 14. In front of the presser foot is a felling folder 15 for interfolding the edge portions of the fabric sections. The material is fed off the end of the work supporting arm by a feed dog 16 carried by a feed bar 17. The feed bar 17 at its rear end is forked and is mounted to slide on a supporting pin 18 carried by an oscillating rock frame 19.

This frame 19 is oscillated by means of a link 20 connected to a ball crank 21 which in turn is oscillated by an eccentric strap 22 cooperating with an eccentric 23 on the main shaft 4. The swinging frame 19 is connected by a link 24 to the feed bar. This imparts endwise movements to the feed bar. The feed dog is raised and lowered by means of a lever 25 carrying a link 26 which is attached to the feed bar and this lever 25 is oscillated by an eccentric strap 27 cooperat-

90 ing with an eccentric 28 on the main shaft 4.

The feeding mechanism forms no part of

the present invention, and is shown de-

scribed and claimed in my copending appli-

95 cation Serial No. 276,783, filed May 10, 1928.

Cooperating with the needle 9 is a looper 29 and cooperating with the needle 10 is a

100 looper 30. These loopers are mounted on a

looper carrier 31 and the looper carrier is

clamped to a supporting shaft 32 mounted to

105 oscillate in suitable bearings 33 and 34 car-

ried by the work supporting arm. This

shaft oscillates freely in its bearings but has

no endwise movement, and, therefore, the

110 looper carrier oscillates in a vertical plane

containing the line of feed. The loopers are,

therefore, two motion loopers and have

115 a forward movement into their respective

thread loops and a retracting movement out

120 of the same.

The looper carrier is oscillated by means

125 of a link 35 which is pivoted at one end to

the carrier and is pivoted at its other end to a crank pin 36 carried by a rock shaft

37. This rock shaft is provided with an

130 arm 38. Mounted adjacent the rock shaft

37 is a second rock shaft 39. This rock

shaft carries an arm 40 which is connected

135 by means of a link 41 to the arm 38 mounted

on the rock shaft 37. The rock shaft 39 also

carries an arm 42 provided with a ball stud

43. A link 44 is connected to this ball stud

43 and the link at its upper end is connected

140 to a crank 45 mounted on an eccentric 46

which is attached to the main shaft 4.

As the main shaft 4 rotates the link 44

will be moved endwise and this will oscillate

the rock shaft 39 which through the link

31 oscillates the rock shaft 37 and this rock

145 shaft through the link 35 oscillates the loop-

70

130

er carrier. The crank 36 on the rock shaft 37 moves from a position which is substantially vertical when the loopers are at the rearward end of their stroke to a position which is substantially horizontal when the loopers are at the forward end of their stroke. As a result the horizontal movements imparted to the link 35 and the forward movement thus imparted to the loopers will decrease in speed as the looper moves into the needle thread loop. The arm 40 and link 41 are more nearly in alignment when the looper is at the forward end of its stroke than when the looper is at the rear end of its stroke. This, together with the position of the eccentric on the main shaft, enables the looper to be given an appreciable dwell when it reaches the forward end of its stroke, and thus it is that the length of stroke of the looper may be made relatively short which is another contributing factor to a high speed machine. As noted above the looper has no lateral movement but merely moves back and forth in a single plane and this is a third contributing factor to a high speed machine wherein there is comparatively little vibration incident to the rapid movement of the parts.

Inasmuch as the loopers have no needle avoiding movement a loop spreader is necessary in order to position the looper thread loops for the needles to enter. The loop spreader is indicated at 48. This loop spreader is mounted on a support 49. The support 49 is carried in part by a rod 50 to which it is attached by means of a set screw, and in part by the looper supporting shaft 32. The support for the loop spreader has a forked end which straddles this loop supporting shaft. This prevents the support for the loop spreader from turning about the axis of the supporting rod 50. The rod 50 is moved endwise by a bell crank lever 51 said lever being pivoted at 52, and provided with a forked end which straddles a pin 53 carried by the rod 50. When the bell crank is oscillated it will impart an endwise movement to the rod 50 and this will impart to the loop spreader carried thereby a movement in a line at right angles to the plane of oscillation of the loopers. The loop spreader is provided with a shank portion 54 which extends into a supporting socket carried by the loop spreader support and is held therein by a set screw 55. The loop spreader at the upper portion thereof is bent so as to be positioned in a line at right angles to the longitudinal axis of the supporting shank 54. This right angle portion 56 of the loop spreader overhangs the loopers. The feed dog 16 is provided with an opening 57 through which the portion 56 of the loop spreader projects and operates. On the under face of the loop spreader there are two spaced shoulders or fingers 58 and

59. These shoulders are so positioned that when the loop spreader is moved laterally the looper thread *a* of the looper 30 is engaged by the shoulder 58 while the looper thread *b* of the looper 29 is engaged by the shoulder 59.

As clearly shown in Fig. 9 this movement of the loop spreader carries the shoulders into engagement with the threads of the loopers and causes the threads of the loopers to be deflected away from the body of the loopers so that the needles 9 and 10 may enter their respective looper thread loops. The strand of the looper thread loop which is engaged by the shoulders is the strand of the loop running from the eye of the looper to the previous stitch, and therefore, when the loopers are retracted, a looper thread loop will be left about each needle.

The bell crank lever 51 is oscillated by means of a link 60. The link 60 is connected to a ball stud 61 carried by an arm 62 secured to a yoke member 63, which yoke member is mounted for free oscillation on the shaft 39. Attached to this yoke member is an arm carrying a ball stud 64. An eccentric strap 65 cooperating with the eccentric member 46 on the main shaft 4 oscillates the yoke and through the yoke moves the link 61 endwise. This endwise movement of the link will oscillate the bell crank and the bell crank will, in turn move the loop spreader back and forth. The loop spreader has only two motions which are back and forth in the direction of its length and said spreader is timed so as to accomplish the spreading of the looper thread loops in the manner above stated.

It will be noted that the operating parts for the loopers and the spreader except the eccentric members carried by the main shaft are all mounted in the work supporting arm which is capable of being detached from the depending member 14. Thus it is that these parts may be assembled in the work supporting arm and the arm afterwards attached to the depending member. This greatly facilitates the assembling of the parts of the machine.

It will be noted from the above description that I have provided a looper operating mechanism having a suspended work supporting arm which consists of few parts, all of which are positively actuated so that the machine may be operated at very high speed with comparatively little resulting vibration. Mounted on the looper carrier is a rearwardly projecting plate 66 provided with thread guiding slots 67, 67. The looper threads are led along the inside of the work supporting arm to the thread guiding eyes 68 and from these thread guiding eyes the threads pass to the guiding slots 67 and then to the loopers. The thread guiding eyes 68 are disposed at some dis-

tance above the thread guiding slots 67 when the loopers are clear back and these thread guiding slots move outwardly and downwardly away from the thread guiding eyes 68 so as to pull upon the looper thread as the loopers reach the rear end of their strokes. It is at this time that the loops are being drawn up which have been concatenated to form the stitches.

10. It is obvious that minor changes in the details of construction and the arrangement of the parts may be made without departing from the spirit of the invention as set forth in the appended claims.

15. Having fully described my invention what I claim as new and desire to secure by Letters Patent, is:

1. In a sewing machine a work supporting arm, means for feeding the material lengthwise of the arm, a looper, means disposed at the free end of the arm for supporting said looper for oscillation in a fixed vertical plane parallel with the feed, and a loop spreader movable in a fixed path at right angles to the plane of movement of the looper for engaging the looper thread and positioning the same so that the needle will pass into the looper thread loop.

2. In a sewing machine a work supporting arm, means for feeding the material lengthwise of the arm, a looper, means disposed at the free end of the arm for supporting said looper for oscillation in a fixed vertical plane parallel with the feed, and in a direction opposed to the direction of feed when entering the needle thread loop, and a loop spreader movable in a fixed path at right angles to the plane of movement of the looper for engaging the looper thread and positioning the same so that the needle will pass into the looper thread loop.

3. In a sewing machine a work supporting arm, means for feeding the material lengthwise of the arm, a looper, means disposed at the free end of the arm for supporting said looper for oscillation in a fixed vertical plane parallel with the feed, a loop spreader, a support for the loop spreader movable transversely of the plane of movement of the looper, and means extending lengthwise of the arm for moving said support endwise.

4. In a sewing machine a work supporting arm, means for feeding the material lengthwise of the arm, a looper, means disposed at the free end of the arm for supporting said looper for oscillation in a fixed vertical plane parallel with the feed, and in a direction opposed to the direction of feed when entering the needle thread loop, a loop spreader, a support for said loop spreader movable endwise in a direction at right angles to the plane of oscillation of the looper, and means extending lengthwise of

the work supporting arm for moving said support endwise.

5. In a sewing machine a work supporting arm, means for feeding the material lengthwise of the arm, a looper, means disposed at the free end of the arm for supporting said looper for oscillation in a fixed vertical plane parallel with the feed, a loop spreader, a support therefor disposed at the free end of the arm and movable at right angles to the plane of oscillation of the looper, and means extending lengthwise of the work supporting arm for moving said support endwise.

6. In a sewing machine a work supporting arm, means for feeding the material lengthwise of the arm, a looper, means disposed at the free end of the arm for supporting said looper for movement in a fixed plane parallel with the feed, a loop spreader, a rod mounted for endwise reciprocation at the free end of the work supporting arm in a direction at right angles to the plane of oscillation of the looper, a support for the spreader attached to said rod, means for moving the rod endwise for causing the loop spreader to engage the looper thread and position the same so that the needle will pass into the looper thread loop.

7. In a sewing machine a work supporting arm, means for feeding the material lengthwise of the arm, a looper, a looper carrier, a shaft on which said looper carrier is mounted, said shaft being disposed at the free end of the work supporting arm and in a line at right angles to the line of feed, means for oscillating said shaft so as to move the looper back and forth in a single plane parallel with the feed, a loop spreader movable in a fixed path at right angles with the plane of movement with the looper for engaging the looper thread and positioning the same so that the needle will pass into the looper thread loop.

8. In a sewing machine a work supporting arm, means for feeding the material lengthwise of the arm, a looper, a looper carrier, a shaft on which said looper carrier is mounted, said shaft being disposed at the free end of the work supporting arm and in a line at right angles to the line of feed, means for oscillating said shaft so as to move the looper back and forth in a single plane parallel with the feed, and in a direction opposed to the direction of feed when entering the needle thread loop, and a loop spreader movable in a fixed path at right angles to the plane of movement of the looper.

9. In a sewing machine a work supporting arm, means for feeding the material lengthwise of the arm, a looper, a looper carrier, a shaft on which said looper carrier is mounted, said shaft being disposed at the free end of the work supporting arm and in

5 a line at right angles to the line of feed, means for oscillating said shaft so as to move the looper back and forth in a single plane parallel with the feed, a loop spreader, a support for the spreader, a rod on which said support is mounted, said rod being disposed at the free end of the work supporting arm and movable endwise in a direction at right angles to the plane of oscillation of the looper.

10 10. In a sewing machine a work supporting arm, means for feeding the material lengthwise of the arm, a looper, a looper carrier, a shaft on which said looper carrier is mounted, said shaft being disposed at the free end of the work supporting arm and in a line at right angles to the line of feed, means for oscillating said shaft so as to move the looper back and forth in a single plane parallel with the feed, a loop spreader, a support for the spreader, a rod on which said support is mounted, said rod being disposed at the free end of the work supporting arm and movable endwise in a direction at right angles to the plane of oscillation of the looper, said support having free sliding engagement with the looper shaft so as to prevent the rod from oscillating.

15 11. In a sewing machine a work supporting arm, means for feeding the material lengthwise of the arm, a looper, a looper carrier, a shaft on which said looper carrier is mounted, said shaft being disposed at the free end of the work supporting arm and in a line at right angles to the line of feed, means for oscillating said shaft so as to move the looper back and forth in a single plane parallel with the feed, and movable in a direction opposed to the direction of feed 20 when entering the needle thread loop, a loop spreader, a support therefor, a rod on which said support is mounted, said rod being movable endwise at the free end of the arm in a direction at right angles to the plane of oscillation of the looper, means extending lengthwise of the arm for moving said rod, and means for preventing said rod from oscillating.

25 12. In a sewing machine a work supporting arm, means for feeding the material lengthwise of the arm, a looper, a looper carrier, a shaft on which said looper carrier is mounted, said shaft being disposed at the free end of the work supporting arm and in a line at right angles to the line of feed, means for oscillating said shaft so as to move the looper back and forth in a single plane parallel with the feed, and movable in a direction opposed to the direction of feed 30 when entering the needle thread loop, a loop spreader, a support therefor, a rod on which said support is mounted, said rod being movable endwise at the free end of the arm in a direction at right angles to the plane of oscillation of the looper, means extending

lengthwise of the arm for moving said rod, said support for the loop spreader having a forked portion having free sliding engagement with the looper shaft so as to prevent the rod from oscillating.

70 13. In a sewing machine a work supporting arm, means for feeding the material lengthwise of the arm, a looper, means disposed at the free end of the arm for supporting said looper for movement in a fixed plane parallel with the feed, a loop spreader having a shank and a portion extending at right angles to the shank which overlies the looper, said overlying portion having a shoulder to engage the looper thread, a support for the shank, means for moving said support whereby the loop spreader is moved back and forth in a fixed path at right angles to the plane of movement of the looper.

75 14. In a sewing machine a work supporting arm, means for feeding the material lengthwise of the arm, a looper, a looper carrier, a looper shaft at the free end of the work supporting arm and extending at right angles to the line of feed whereby said looper may be oscillated in a fixed plane parallel with the line of feed, a link extending lengthwise of the work supporting arm for oscillating said shaft, a rock shaft having a crank to which said link is connected, said crank being disposed so as to move toward and from a horizontal position as the looper moves into and out of the needle thread loop, an arm carried by said rock shaft, a second rock shaft having an arm, a link connecting the arms on the two rock shafts and movable toward and from a dead center line when the looper moves into and out of the needle thread loop.

80 15. In a sewing machine a supporting base, an overhanging bracket carried thereby, a frame mounted at the upper outer end of said bracket, a main shaft disposed in said frame, a depending member at one end of said frame, a work supporting arm suspended by said depending member, means for feeding the material lengthwise of the arm and off the end thereof, a looper disposed at the free end of the arm and oscillating in a fixed vertical plane parallel with the line of feed, a loop spreader movable in a fixed path at right angles to the plane of oscillation of the looper, devices extending through said depending member and lengthwise of said arm for oscillating said looper, and devices extending through said depending member and lengthwise of said arm for moving said loop spreader.

85 16. In a sewing machine a supporting base, an overhanging bracket carried thereby, a frame at the upper outer end of said bracket, a main shaft mounted in said frame, a depending member carried by said frame at one end of said shaft, a work supporting
